PROCESS OF REFINING VEGETABLE OILS

Benjamin H. Thurman, Bronxville, N. Y., assignor
to Refining, Inc., Reno, Nev., a corporation of
Nevada

Application December 29, 1938, Serial No. 248,357

15 Claims. (Cl. 260—425)

This invention relates to a process of refining vegetable oils, and more particularly to the alkali refining of vegetable oils in which substantially all of the oil is recovered as high quality oil from the soap stock resulting from adding the alkali to the oil.

In known processes for the alkali refining of vegetable oil, considerable neutral oil is lost by entrainment of the same in the soap stock separated from the oil. Recovery of such oil is difficult, and even if recovered it is of a poor quality. In accordance with the present invention, the oil is conditioned for alkali refining and the alkali treating step is carried out so that the soap stock resulting from alkali refining is capable of being treated in a simple manner to recover high quality oil. Any gummy materials such as phosphatides, proteins, resins, etc., are removed as far as practicable before treating the oil with an alkali refining reagent. This conditions the oil so that the soap stock produced is relatively free of such gummy materials. In general, such soap stock is lighter in weight and less compact than soap stock containing gums. The layer of soap stock admixed with oil after a soap stock settling operation is, therefore, greater in depth and contains more entrained oil than in conventional batch refining processes. Because of the absence of substantial amounts of gums, however, the oil retained in the soap stock can be easily recovered. Dilution with water or aqueous solutions of salts followed by continuous centrifugal separation recovers substantially all of the oil in high quality form, although emulsion difficulties due to the presence of gums are encountered when this operation is attempted with ordinary soap stock resulting in still leaving a substantial quantity of oil in the soap stock. Also, such treatment of ordinary soap stock produces a low quality oil usually requiring another refining operation. Since the soap stock produced in the present invention is relatively free of gums, the oil may also be recovered therefrom by solvent extraction with oil solvents to produce an oil which is not contaminated with gummy impurities soluble in the solvents, and filtration steps may be employed as part of the solvent extraction without blocking the filter elements with gummy materials.

It is, therefore, an object of the present invention to provide a process of refining vegetable oils in which high quality oils are recovered from the soap stock and refining losses are minimized.

Another object of the invention is to provide a process of refining vegetable oils in which alkali refining is carried out under conditions which will produce a soap stock which is capable of being treated to recover high quality oil. 5

A further object of the invention is to provide a process of refining vegetable oils in which an alkali treating step may be carried on as a batch operation and a soap stock is produced which is capable of being treated to recover entrained oil 10 as high quality oil.

Other objects and advantages of the invention will appear in the following description of the invention, given in conjunction with the attached drawing, which is a schematic diagram of an apparatus capable of carrying out a preferred process. 15

Referring more particularly to the drawing, a crude oil to be refined may be withdrawn from a 20 source of supply shown as a tank 10 by a pump 11 and delivered through a heat exchange device 12 to a mixer 13. The heat exchange device may include a coil 14 through which the oil is passed, which coil is positioned in a casing 15 through 25 which any desired heating or cooling medium may be circulated. A degumming reagent is withdrawn from a source of supply shown as a tank 16 by means of a pump 17 and delivered to the mixer 13. The tanks 10 and 16 may be provided with heating coils 18 and 19, respectively, through which any desired heating medium may be circulated to bring the oil and degumming reagent to desired temperatures for introduction 30 in the process. The pumps 11 and 17 may be driven by a variable speed motor 20 with a variable speed device 21 positioned between the motor 20 and the pump 11 in order that proportioned streams of oil and degumming reagent 35 may be delivered to the mixer 13, although any other suitable type of apparatus may be employed. The mixing device 13 may be any suitable flow mixer, such as a device for injecting the degumming reagent at right angles into a 40 stream of the oil, although a mechanical agitator 45 may be employed.

The degumming reagent, which may be water, causes gummy materials such as phosphatides, proteins, resins, etc., to be precipitated in the 50 oil as froths which are capable of being separated by difference in specific gravity. Preferably the mixture of oil and froths with excess water or other degumming reagent is passed through a second heat exchanger 22 similar to the heat 55

exchanger 12 and delivered to a continuous centrifugal separator 23. This centrifugal separator is preferably of the heated type disclosed in Patent No. 2,100,277, granted November 23, 1937, but may be of any suitable type capable of continuously centrifugally separating precipitated gums from the oil. The precipitated gums, along with excess degumming reagent, are discharged as the heavy effluent through a spout 24 into a receiver 25. The degummed oil is discharged as the light effluent through a pipe 26 and in many cases it is preferable to pass the degummed oil through a heat exchange device 27 to cool the oil prior to delivering the same into a storage tank 28. The storage tank 28 may be an open tank, but is preferably closed and provided with a vent 29. The prior degumming of the oil conditions the same for the production of a soap stock from which high quality oil may be recovered as hereinafter described.

A suitable manner of alkali treating the oil is to deliver the same through a pipe 30 from the tank 28 into a receptacle or kettle 31 which may be similar to conventional batch refining kettles. Alternatively, the tank 28 may be eliminated and the oil delivered directly into the kettle 31 through a pipe 31'. The kettle 31 may be provided with an agitator 32 driven from any suitable source of power through the pulley or sprocket 33. The kettle may be also provided with a heating coil 34 through which any desired heating medium may be circulated and may further be provided with a heating jacket 35 through which any desired heating medium can be circulated. Either the heating coil 34 or the heating jacket 35, or both, may be employed, depending upon the oil being treated and the rapidity with which it is desired to heat materials in the kettle 31. After a body of oil has been placed in the kettle 31, the agitator 32 is ordinarily started and an alkali refining solution, usually an aqueous solution of caustic alkali such as caustic soda, is run in through the pipe 36 until sufficient alkali has been added to neutralize the free fatty acids and provide an excess for color reduction, particularly if highly colored oils are being refined. Agitation is then discontinued, and the soap stock produced by neutralization of the free fatty acids is allowed to settle. When settling of the soap stock has progressed to the desired extent, clear refined oil may be withdrawn from the kettle 31 through a pipe 37 and delivered by a pump 38 into a receiver 39. The pipe 37 is usually a flexible conduit or is adjustable in length so that substantially all of the clear oil may be withdrawn from the kettle 31, leaving a layer of soap stock admixed with neutral oil but relatively free of gums.

Sufficient water or an aqueous solution of salt as hereinafter explained may then be run into the kettle through a pipe 40, while the agitator 32 is being rotated until a flowable mixture of soap stock is produced. The flowable soap stock mixture may then be withdrawn from the kettle 31 by means of a pump 41 and delivered to a mixer 42. Additional water or aqueous salt solution may be withdrawn from a tank 43 by means of a pump 44 and delivered to the mixer 42. The pumps 41 and 44 may be driven by a variable speed motor 45 with a variable speed device 46 between the pump 41 and the motor 45, although other suitable mechanisms may be employed. The tank 43 may be provided with a heating coil 44 through which any desired heating medium

may be circulated in order to bring the temperature of the added water or aqueous solution to a desired mixing temperature.

In many operations, it is feasible to add sufficient water in the kettle 31 so that the tank 43, pump 44 and mixer 42 may be eliminated and the soap stock mixture from the kettle 31 delivered by the pump 41 to a continuous centrifugal separator 47. It is usually desirable to pass the soap stock mixture through a heat exchange device 48 in order to bring the same to the most effective temperature for centrifugal separation. The heat exchanger 48 is employed when the temperature of the mixture in the kettle 31 differs from the most effective temperature for centrifugal separation, but may be eliminated if the temperature of the materials in the kettle 31 is suitable for centrifugal separation. The added diluting agent is then admixed with the oil and soap stock just before it enters the centrifugal separator 47. The centrifugal separator 47 continuously separates neutral oil from the diluted soap stock, and this oil is discharged as the light effluent through a spout 49 into a receiver 50. The soap stock, along with the added water, or aqueous solution, is discharged as the heavy effluent through a spout 51 into a receiver 52. The centrifugal separator 47 is also preferably of the heated type above referred to, but may be of any type suitable for separating oil from soap stock.

By removing the gums from the oil prior to alkali refining, substantially no gums are present in the soap stock settled from the oil in the kettle 31. The absence of gums in this soap stock, however, renders the soap stock lighter and more difficult to settle, so that conventional batch refining of degummed oil is not practicable, unless the oil is recovered from the soap stock, as large amounts of neutral oil are entrained therewith. That is to say, the presence of the gums in the soap stock in conventional batch refining provides for a cleaner separation of the soap stock from the oil in batch refining. However, a considerable amount of oil is entrained in the soap stock, even with the gums present therein, and attempts heretofore made to recover this oil from the soap stock containing the gums have resulted in inferior quality oil. I have discovered that, although a larger amount of oil is entrained with the soap stock, this oil can be recovered as high quality oil by diluting the soap stock and then subjecting the resulting mixture to continuous centrifugal separation. By operating in this manner, substantially all of the oil can be separated from the soap stock as high quality oil, and it is unnecessary to run the entire amount of oil being refined through the centrifugal separator 47, as a large portion of the oil may be withdrawn as high quality refined oil from the kettle 31 through the pipe 37. The capacity of the centrifugal separator 47 or the number of centrifugal separators employed, if more than one is used, can, therefore, be reduced.

It is apparent that some oil will be entrained with the gums separated from the oil in the centrifugal separator 23 and discharged into the receiver 25. It is possible to carry on the degumming step of the process as a batch operation in which the degumming reagent, such as water, is mixed with the oil in a kettle and the gums allowed to settle from the oil. In such batch degumming operations, however, the oil is subjected to relatively high temperatures for extended periods of time in the presence of the gums and with many oils which are relatively

highly colored, the color is set in the oil so that this color is not sufficiently reduced in subsequent refining and bleaching steps. Also, a large amount of oil is entrained in the gums if degumming is carried on in a batch operation such that refining losses are increased. A continuous degumming operation is, therefore, preferable in the present invention.

In such degumming operations, it has been found that the temperature of mixing the degumming reagent with the oil for most efficient precipitation of the gums will depend upon the oil being treated and also the most effective temperature for separating the precipitated gums from the oil as well as the time of treatment between mixing and separation will depend upon the oil being treated and the temperature of treatment. The heating coil 18 in the crude oil tank 10 may be employed to raise the temperature of the oil and reduce its viscosity until it is a freely flowing liquid. The heat exchanger 12 may be employed to bring the oil to the desired temperature of mixing. The heating coil 19 in the degumming reagent tank 16 may also be employed to bring the degumming reagent to the desired temperature for mixing with the oil. No specific temperature of mixing applicable to all oils can be given, as this temperature may vary from room temperature, i. e., 70° F. or below, to as high as 160° F. The heat exchanger 22 may be employed to adjust the temperature of the resulting mixture to that found most effective for separation in the centrifugal separator 23. This temperature will vary with the nature of the oil being treated and the amount and nature of the degumming reagent employed. This temperature may likewise vary from 70° F. or lower up to 160° F. With certain oils, with which the temperature of mixing and the temperature of separation is the same, the heat exchanger 22 may be omitted or employed to provide a treating period between mixing and separation. The degumming reagent may be water alone or aqueous solutions of weak acids or alkalies or neutral salts as disclosed in my copending application Serial No. 248,355 filed December 29, 1938. The sodium thiosulfate and equivalent solutions therein disclosed reduce the viscosity of the gums and their use minimizes the amount of oil entrained in the gums. Depending upon the oil being treated, the amount of degumming reagent may be as low as 1 or 2%, although with other oils the amount of water or other degumming reagent may be as high as 25% or even higher. If the temperature of separation in the centrifugal separator 23 is in the upper portion of the range mentioned, it may be desirable to cool the oil by passing the same through the heat exchanger 27 prior to delivering the same to the storage tank 28 or into the kettle 31. With certain oils containing very small amounts of gums, the amount of degumming reagent may be very small, such that very little oil is entrained in the gums separated from the oil and with other oils in which no substantial amounts of gums are present because of prior degumming operations or the nature of the process by which the oils were produced, the degumming operation of the present invention may sometimes be omitted.

With most oils, it is preferable to start kettle refining with the oil at a relatively low temperature, for example, between 70 and 90° F., although with some oils it is possible to mix the alkali therewith at somewhat higher temperatures. With the alkali ordinarily employed, that

is, caustic alkali, some of the neutral oil is saponified to produce a refining loss. The lower the temperature of the oil in the refining kettle 31 during the mixing and neutralization of the free fatty acids, the less the amount of neutral oil 5 saponified. It is, therefore, desirable to start the kettle refining operation at as low a temperature as practicable. Agitation of the oil with the alkali solution at these low temperatures ordinarily produces an inseparable emulsion which must be 10 heated in order to produce a "break," and this heating may be accomplished with either the heating coil 34, or the heating jacket 35, or both. Slow agitation is usually employed during such heating, and the heating is continued until the 15 break is produced. Heating and agitation are then discontinued and the soap stock allowed to settle from the oil.

After the clear oil has been withdrawn from the kettle by the pipe 37, sufficient water is introduced through the pipe 40 to produce a flowable mixture of soap stock and water. This water may be at an elevated temperature corresponding to that of the temperature of the soap stock in the kettle, so that it is unnecessary to further heat 25 the mixture in the heat exchanger 48. If cold water is employed, it will ordinarily be necessary to raise the temperature in the mixture either by heating with the heating jacket 35 or the heating coil 34 positioned in the kettle or by heating the 30 mixture in the heat exchanger 48. The most effective temperature of separation in the centrifugal separator 41 will depend upon the nature of the oil and soap stock being processed, but will usually be between 110 and 160° F. 35

As the excess caustic alkali employed to neutralize the oil in the kettle 31 continues to attack neutral oil as long as it is in contact therewith, and considerable time is required to obtain maximum settling of the soap stock from the oil in 40 the kettle 31, refining losses due to saponification of neutral oil may many times be reduced by settling for a shorter period of time, then removing clear oil from a kettle through the pipe 37 prior to maximum settling of the soap stock. A 45 layer of soap stock and oil in which relatively large proportions of oil are present is then left in the kettle and by again starting the agitator 32 to prevent further stratification of the soap stock, a pumpable mixture of oil and soap stock 50 may be withdrawn from the kettle 31. If necessary for most efficient separation, additional water may be delivered into the kettle through the pipe 40, or, alternatively, additional water may be withdrawn from the tank 43 and mixed 55 with the flowing stream of oil and soap stock in the mixer 42 prior to centrifugal separation. By this procedure the time of settling in the kettle is markedly reduced so that refining losses due to saponification of neutral oil are reduced and 60 substantially all of the oil remaining in the soap stock can be separated therefrom in the centrifugal separator 41. Also, the capacity of the centrifugal separator or separators 41 can be reduced over that required for separating all of the 65 oil treated in the process from the soap stock by centrifugal separation.

The water added to the soap stock in either the kettle 31 or the mixer 42 may contain relatively large proportions of neutral or alkaline salts such 70 as sodium chloride, sodium sulfate, sodium silicate, sodium carbonate or equivalent potassium salts, that is to say, the neutral salts of alkali metals or the alkali metal salts of weak acids, in order to add weight to the soap stock separated 75

from the neutral oil or at least in part cause the soap to grain out of neutral oil. Other processes of recovering the oil from the soap stock free from gums are also practical. For example, it is possible to add an oil solvent, for example, a mineral oil solvent such as gasoline or kerosene, to the mixture of oil and soap stock. In such case, the oil-soap stock mixture diluted with the solvent may be centrifugally separated to separate the oil and solvent as the light effluent and the soap stock as the heavy effluent. The solvent may, of course, be recovered from the oil by distillation, preferably in a vacuum, and re-used in the process. Furthermore, the soap stock may be filtered from the oil solvent mixture and the soap stock residue washed with solvent in order to recover substantially all of the oil. For such solvent treatment of the soap stock, it is advantageous to dehydrate the soap stock-oil mixture, for example, by flowing the same into a vacuum chamber to remove substantially all of the water and any vaporizable impurities contained therein prior to mixing the solvent. Such an operation can be carried out in this manner in a vacuum chamber such as that disclosed in the copending application of Benjamin Clayton, Serial No. 237,999 filed October 31, 1938, and such dehydration process is also advantageous prior to mixing with water or other wetting solution, as also disclosed in said application. It will thus be seen that I have provided an improved process of refining vegetable oils containing gums and free fatty acids, for example, cotton-seed oil, soya bean oil, corn oil, sesame oil, etc.

35 While I have disclosed the preferred embodiments of my invention, it is understood that details thereof may be varied within the scope of the following claims.

What I claim is:

40 1. The process of refining vegetable oils, which comprises, treating said oils to remove gums contained therein, thereafter mixing a body of said oil with an alkali refining agent and settling the resulting soap stock from the oil to produce a soap stock-oil mixture substantially free of gums, withdrawing refined oil from said settled soap stock, and thereafter diluting the soap stock and separating additional oil from said soap stock.

2. A process of refining vegetable oils containing gums and free fatty acids, which comprises, continuously mixing a degumming reagent with said oil to precipitate said gums and continuously centrifugally separating said gums from said oil, thereafter admixing a body of said oil with an alkali refining reagent and settling the resulting soap stock from said oil, withdrawing refined oil from said settled soap stock and admixing the remaining soap stock containing entrained oil with a diluting agent, and separating oil from said soap stock.

65 3. The process of refining vegetable oils, which comprises, treating said oils to remove gums contained therein, thereafter mixing a body of said oil with an alkali refining reagent and settling the resulting soap stock from the oil to produce a soap stock-oil mixture substantially free of gums, withdrawing refined oil from said settled soap stock, and thereafter diluting the soap stock with water and separating additional oil from said soap stock.

70 4. The process of refining vegetable oils, which comprises, treating said oils to remove gums contained therein, thereafter mixing a body of said oil with an alkali refining agent and settling the resulting soap stock from the oil to produce a

75 soap stock-oil mixture substantially free of gums, withdrawing refined oil from said settled soap stock, and thereafter diluting the soap stock with water to form a flowable mixture and continuously centrifugally separating additional oil from said soap stock.

5. The process of refining vegetable oils, which comprises, treating said oils to remove gums contained therein, thereafter mixing a body of said oil with an alkali refining agent and settling the resulting soap stock from the oil to produce a soap stock-oil mixture substantially free of gums, withdrawing refined oil from said settled soap stock, and thereafter diluting the soap stock with an aqueous solution of a salt which will not attack the neutral oil and continuously centrifugally separating additional oil from said soap stock.

6. The process of refining vegetable oils, which comprises, treating said oils to remove gums contained therein, thereafter mixing a body of said oil with an alkali refining agent and settling the resulting soap stock from the oil to produce a soap stock-oil mixture substantially free of gums, withdrawing refined oil from said settled soap stock, and thereafter diluting said settled soap stock with an oil solvent and separating additional oil in admixture with said solvent from said soap stock.

7. The process of refining vegetable oils, which comprises, subjecting an oil which is substantially free of gumming material to treatment including admixing a body of said oil with an alkali refining reagent and settling from said oil a soap stock substantially free of gummy material, and thereafter diluting the soap stock to form a flowable mixture and separating additional refined oil from said soap stock.

8. The process of refining vegetable oils, which comprises, subjecting an oil which is substantially free of gumming material to treatment including admixing a body of said oil with an alkali refining reagent and settling from said oil a soap stock substantially free of gummy material, and thereafter diluting the soap stock with water to form a flowable mixture and continuously centrifugally separating additional oil from said soap stock.

9. The process of refining vegetable oils, which comprises, subjecting an oil which is substantially free of gumming material to treatment including admixing a body of said oil with an alkali refining reagent and settling from said oil a soap stock substantially free of gummy material, and thereafter diluting the soap stock with an oil solvent and separating said solvent along with additional refined oil from said soap stock.

10. The process of refining vegetable oils, which comprises, subjecting an oil which is substantially free of gumming material to treatment including admixing a body of said oil with an alkali refining reagent and settling from said oil a soap stock substantially free of gummy material, dehydrating said soap stock, and thereafter admixing a diluting agent with said soap stock and separating additional refined oil from said soap stock.

11. The process of refining vegetable oils, which comprises, subjecting an oil which is substantially free of gumming material to treatment including admixing a body of said oil with an alkali refining reagent and settling from said oil a soap stock substantially free of gummy material, dehydrating said soap stock, and thereafter extracting additional refined oil from the soap stock with an oil solvent.

12. A process of refining vegetable oils containing gums and free fatty acids, which comprises, continuously mixing a degumming reagent with said oil to precipitate said gums and continuously centrifugally separating said gums from said oil, thereafter admixing a body of said oil with an alkali refining reagent and settling the resulting soap stock from said oil, withdrawing refined oil from said settled soap stock and admixing the remaining soap stock containing entrained oil with a diluting agent and continuously centrifugally separating additional refined oil from said soap stock. 5
13. A process of refining vegetable oils containing gums and free fatty acids, which comprises, continuously mixing a degumming reagent with said oil to precipitate said gums and continuously centrifugally separating said gums from said oil, thereafter admixing a body of said oil with an alkali refining reagent and settling the resulting soap stock from said oil, withdrawing refined oil from said settled soap stock and admixing the remaining soap stock containing entrained oil with sufficient water to form a flowable mixture and continuously centrifugally separating additional refined oil from said soap stock. 10
14. A process of refining vegetable oils containing gums and free fatty acids, which comprises, continuously mixing a degumming reagent with said oil to precipitate said gums and continuously centrifugally separating said gums from said oil, thereafter admixing a body of said oil with an alkali refining reagent and settling the resulting soap stock from said oil, withdrawing refined oil from said settled soap stock, admixing the remaining soap stock with an oil solvent, and separating additional refined oil in 15 solution in said solvent from said soap stock. 15
15. A process of refining vegetable oils containing gums and free fatty acids, which comprises, continuously mixing a degumming reagent with said oil to precipitate said gums and continuously centrifugally separating said gums from said oil, thereafter admixing a body of said oil with an alkali refining reagent and settling the resulting soap stock from said oil, withdrawing refined oil from said settled soap stock, subjecting said soap stock to vacuum treatment to remove water and other vaporizable materials therefrom and thereafter admixing the resulting dehydrated soap stock with a diluting agent and separating additional refined oil from said soap stock. 20
